STRINGED MUSICAL INSTRUMENT

Walter J. Pelensky, 19C Manheim Gardens,
Philadelphia, Pa. 19144

Filed Dec. 8, 1969, Ser. No. 20,393

Term of patent 14 years

Int. Cl. D17—03

U.S. Cl. D56—1

Fig. 4

Fig. 3

FIG. 1 is a perspective view of a stringed musical instrument, specifically an Ukrainian Kobza of the Tambur (Tanbur) class, showing my new design;

FIG. 2 is a fragmentary perspective view thereof, showing the peghead from a different angle;

FIG. 3 is a face view; and

FIG. 4 is a left side elevational view thereof, the strings being omitted for convenience in illustration.

I claim:

The ornamental design for a stringed musical instrument, as shown and described.
